FACE LIFTING BAND

Lorraine A. Basché, 17071 Courtney Lane,
Huntington Beach, Calif. 92647

Filed July 10, 1970, Ser. No. 23,892

Term of patent 14 years

Int. Cl. D24—99; D28—02

U.S. Cl. D83—1

Fig. 1

Fig. 2

Fig. 3

Fig. 4

FIG. 1 is a top perspective view of a face lifting band showing my new design;

FIG. 2 is a front elevational view thereof;

FIG. 3 is a side elevational view thereof;

FIG. 4 is a top plan view thereof.

I claim:

The ornamental design for a face lifting band, as shown.
